UNITED STATES PATENT OFFICE.

ERNST G. HELANDER, OF PITTSBURG, PENNSYLVANIA, ASSIGNOR TO AXEL H. HELANDER,
OF PITTSBURG, PENNSYLVANIA.

BAROMETRIC CONDENSER.

No. 926,486.

Specification of Letters Patent.

Patented June 29, 1909.

Application filed March 9, 1909. Serial No. 482,269.

To all whom it may concern:

Be it known that I, ERNST G. HELANDER, of Pittsburg, in the county of Allegheny and State of Pennsylvania, have invented a new and useful Improvement in Barometric Condensers, of which the following is a full, clear, and exact description, reference being had to the accompanying drawings, forming part of this specification, in which—

10 Figure 1 is a sectional elevation of one form of condenser embodying my invention and Fig. 2 is a similar view of a portion of the condenser and showing a modification.

15 My invention has relation to the class of barometric condenser of the countercurrent type, and is designed to provide a novel and effective arrangement of the steam inlet and tail pipe of the condenser, whereby the friction of the steam entering the vacuum chamber is reduced to a minimum and the steam 20 is brought into effective contact with the condensing water.

25 The nature of my invention will be best understood by reference to the accompanying drawings which will now be described, it being premised, however, that various changes may be made in the details of construction and arrangement of parts without departing from the spirit and scope of my invention as defined in the appended claims.

30 Referring first to the form of my invention as shown in Fig. 1, the numeral 2 designates the upper portion of the condensing chamber, which may be in general of any well known or usual construction.

35 3 designates the vacuum pipe connection which connects with the upper portion of the condensing chamber and is connected with the usual exhaust pump, or other air exhausting means, not shown.

40 4 is the usual water inlet pipe communicating with the chamber at one side, the water discharged from this pipe rising and falling over the interior dome 5 and thence 45 downwardly over the deflectors 6 and 7. Any suitable arrangement of baffles or deflectors may be provided within the condensing chamber for the purpose of causing the water to fall therethrough in sheets or cascades.

50 8 designates the steam inlet pipe which enters the lower enlarged portion 9 of the condensing chamber at the bottom thereof.

10 designates the tail pipe which extends downwardly into a sink or well 11. This

55 pipe is located to one side of the steam inlet 55 pipe 8 and enters the lower portion 9 of the condensing chamber by the bend or elbow 12, terminating concentrically within the chamber 9 with a bowl-shaped enlargement 13, the open upper end of which is of larger 60 diameter than the diameter of the upper portion 2 of the condensing chamber and is directly below the lower end of this upper reduced portion of said chamber. The exhaust steam to be condensed enters the 65 lower portion 9 of the condensing chamber from the pipe 8 and flows around the bowl-shaped enlargement 13 and thence passes inwardly and upwardly into the upper portion 2 of the condensing chamber where it meets 70 the water passing downwardly therethrough and is condensed thereby. By arranging the steam inlet so that it enters the bottom of the condensing chamber, I avoid the use 75 of the elbow which is generally employed for connecting the steam pipe with the side of the condensing chamber and thereby greatly reduce the friction of the steam and the amount of work required of the exhauster. 80 The condensing water together with the condensed steam flows directly into the bowl-shaped enlargement of the tail pipe and is prevented from passing downwardly into the steam pipe 8.

85 In the modification shown in Fig. 2, the construction is in general the same as that shown in Fig. 1 except that the steam pipe 8^a enters the lower portion 9^a of the condensing chamber at one side of the center, and the tail pipe 10^a enters said chamber at 90 the opposite side, the bowl-shaped enlargement 13^a within such chamber being of eccentric instead of concentric form. The operation and advantages are substantially the same as those of the construction shown in 95 Fig. 1, except that this modification has the added advantage of greater compactness since the steam inlet pipe 8^a and the tail pipe 10^a can be arranged closely together and extend upwardly underneath the condensing 100 chamber. In this form of my invention I have also shown the water deflector 6^a as provided with a plurality of relatively small perforations 14.

105 As above stated, I do not limit myself to any particular construction of the upper portion of the condensing chamber nor to the means therein for breaking up the water to

bring it in proper contact with the steam, since any usual or suitable means may be employed for this purpose.

What I claim is:

- 5 1. A barometric condenser of the counter-current type having a steam inlet pipe extending vertically upward through the bottom wall of the condensing chamber, and a tail pipe leading into said chamber at one side of the steam pipe and terminating there-in in an open top enlargement; substantially as described.
- 10 2. A barometric condenser of the counter-current type having its condensing chamber formed with an enlarged lower portion, a steam inlet pipe opening into such enlarged portion at the bottom thereof in a vertical direction, and a tail pipe also entering such enlarged portion at the bottom and to one side of the steam inlet pipe and terminating in an open top enlargement; substantially as described.
- 15 3. A barometric condenser of the counter-current type having a condensing chamber formed with an upper portion provided with a water inlet and with water deflecting

means, and a lower enlarged portion, a steam inlet pipe entering the bottom of such enlarged portion in a vertical direction, and a tail pipe at one side of the steam inlet pipe and having a bowl-shaped enlargement at its upper end within the enlarged portion of the condensing chamber, the bowl-shaped enlargement being of greater diameter than the diameter of the upper portion of the condensing chamber; substantially as described.

4. A barometric condenser of the counter-current type having its condensing chamber enlarged at its lower portion, a steam inlet pipe connected to the enlarged portion of the condensing chamber, and a tail pipe at one side of the steam pipe and terminating at its upper end in an open top enlargement within the enlarged lower portion of the condensing chamber; substantially as described.

In testimony whereof, I have hereunto set my hand.

ERNST G. HELANDER.
